CLAIM

The ornamental design for a holder for an aerosol can
or the like, substantially as shown and described.

DESCRIPTION

FIG. 1 is a side elevational view of a holder for an
aerosol can or the like showing our new design;

FIG. 2 is a perspective view showing the top, front, and
one side;

FIG. 3 is a rear elevational view;

FIG. 4 is a top plan view; and

FIG. 5 is a bottom plan view thereof.
